UNITED STATES PATENT OFFICE.

HIRAM LAWRENCE, OF SALEM, OREGON.

WASHING-MACHINE.

SPECIFICATION forming part of Letters Patent No. 366,411, dated July 12, 1887.

Application filed November 9, 1886. Serial No. 218,415. (No model.)

To all whom it may concern:

Be it known that I, HIRAM LAWRENCE, of Salem, in the county of Marion and State of Oregon, have invented a new and Improved 5 Washing-Machine, of which the following is a specification, reference being had to the annexed drawings, forming a part thereof, in which—

Figure 1 is a side sectional elevation of my 10 improved washing-machine, and Fig. 2 is a vertical transverse section taken on line α α in Fig. 1.

Similar letters of reference indicate corresponding parts in both views.

15 The object of my invention is to provide a simple and efficient machine for washing clothes without the direct application of the hands to the articles being washed and without pounding or friction.

20 My invention consists in a revoluble cylinder mounted in movable bearings fitted to a tub and in gearing for imparting rotary motion to the cylinder.

The upper part of the tub A is of oblong 25 rectangular form, and the lower part consists of a hollow metallic semi-cylinder B. In the ends of the tub are formed dovetail grooves a a' , in which are fitted the bars c c' . In the lower ends of the said bars are formed the 30 bearings of the journals d d' of the cylinder C. The cylinder C is formed of the heads e e' and the slats f , secured to the edges of the heads, with narrow intervening spaces g between the slats. A door, D, is provided at one side 35 of the cylinder, which is connected with the heads e e' by hinges h , and is provided with a hook, i, for holding it in a closed position.

To the journals d of the cylinder C is secured a spur-wheel, E, and to the bar c is secured a right-angled arm, F, in which is supported a pinion, G, on the shaft H, which projects through a slot, i' , in the end of the tub A, and is provided with a crank, I. Upon the screw j , projecting from the side of the bar c ,

through the slot i' , and also upon the shaft H, 45 is placed a clamping-bar, J, which rests against the end of the tub, and, in connection with the screw j , is employed for clamping the bar c in its place in the tub. The top of the tub is closed by a cover, K, which confines the heat, 50 steam, and water to the tub. Legs L secured to opposite ends of the tub support it at a convenient height above the floor. At suitable intervals longitudinal bars k are secured along the inner surface of the walls of the 55 cylinder, and holes l are made in the ends of the cylinder, to permit of the circulation of water.

The clothes to be washed are introduced into the cylinder through the door D, and the 60 tub is partly filled with water, when motion is imparted to the cylinder C by the crank I through the shaft H, pinion G, and spur-wheel E. As the cylinder C is revolved, the clothes are carried upward by the bars k and allowed 65 to fall, thus continually agitating them and causing the water to circulate through them and remove the dirt.

Having thus fully described my invention, I claim as new and desire to secure by Letters 70 Patent—

A washing-machine comprising the tub A, having vertical recesses a a' , a vertical slot, i' , the two vertical bars c c' ; fitting in said recesses, the washing-drum journaled in the lower ends 75 of the said bars, and having a gear-wheel, E, the angle-arm F above the said gear, the shaft H, passing through slot i' , journaled in the bar c , and lower end of arm F, and having the gear G between said arms and meshing with the 80 gear E, the vertical bar J, through which the shaft H passes, and the screw j , passed through the bar J into the upper end of the bar c above the shaft H, substantially as set forth.

HIRAM LAWRENCE.
